GOVERNOR

Albert Kalin, Cleveland, Ohio

Original application March 26, 1941, Serial No. 385,228. Divided and this application September 10, 1941, Serial No. 410,284

3 Claims. (Cl. 264—3)

This application is a division of my application Serial No. 385,228 filed March 26, 1941. In the parent application there is shown a governor for prime movers and other machinery substantially according to my Patent 2,219,229 issued October 22, 1940. Said governor, as in the patent, operates through a hydraulic fluid system including a servo-motor piston and cylinder, under the control of a pilot valve and weighing means, to regulate for instance speed of a Diesel engine to hold the speed constant notwithstanding variations in load on the engine.

The governor has an accumulator system operable automatically to maintain constant positive pressure in the hydraulic system so long as the governor and a suitable pumping system arranged to supply the governor with hydraulic fluid are driven by the engine. The accumulator is spring loaded for operation such as to maintain the desired constant pressure in event of over-delivery by the pumping system and when the engine has been idle for a short time (sometimes a few seconds) the pressure is usually reduced to a low value by operation of the accumulator spring or springs and seepage of hydraulic fluid past various coating working parts, notwithstanding close clearances between said parts. The hydraulic fluid in shutting down, as in the governor shown in the parent application, may purposely be dumped from the regulating servo-motor and connected fluid passages, requiring recharging before the engine can be restarted. Upon restarting, because of initial lack of working hydraulic pressure, at least some time must elapse before the governor can take full control of the engine. This sometimes makes the operation of starting of the engine take longer than it should (e. g. more time than available in certain circumstances) and usually results in waste of starting power (e. g. air supply).

The provision of means separate from the governor to supply hydraulic fluid to the governor at suitable pressure in order to meet the problem outlined above is already known in the art; but, so far as I know, it has not previously been proposed to provide boosting hydraulic pressure means as part of the governor mechanism. The present arrangement utilizes air (or other elastic fluid maintained under pressure for starting purposes) in a special servo-motor, built into the governor, in order to boost the pressure in the regulating hydraulic system of the governor simultaneously with or prior to performing the operation of starting the engine with such air or fluid. The above indicates one object thereof.

The mechanism comprising the principal subject matter of this application will usually be referred to herein for convenience as a "booster-servo."

Another object is to provide a booster-servo cylinder and piston mechanism having shock absorbing means operable in event there is an insufficient supply of hydraulic fluid in the booster-servo cylinder when operation of the booster-servo takes place—or in event the actuating (e. g. air) pressure for the booster-servo is excessive—to damp or cushion said operation.

A further object is to provide a booster-servo mechanism arranged to enable air at high pressure to be used to build up initial oil pressure in a governor, wherein the air and oil have no possibility of becoming mingled in a manner such as might cause improper operation of the governor or an explosion—as will be more fully explained later herein.

Other objects and advantages of the invention will become apparent from the following description of a preferred form thereof, as shown in the drawings, in which:

Fig. 1 is a central sectional view of a speed governor incorporating the invention; Fig. 2 is a plan view of the governor, and Fig. 3 is a vertical sectional view thereof taken as indicated at 3—3 on Figs. 1 and 2.

In the governor mechanism shown herewith as one type of governor on which the booster-servo mechanism may be used, 1 (Figs. 1 and 3) is a base adapted to be mounted on an engine to be governed, 2 a power case surmounting the base, 3 a regulating servo-motor cylinder block attached as at one side of the power case, and 4 a speeder case for the speed responsive or weighing mechanism and adjusting means therefor.

A shaft 10, to be drivingly coupled to the engine, is supported in the base as by a bearing 11 above which is an oil seal 12. The shaft carries a pump gear 13 in a suitable pump chamber formed in the power case as shown in my said patent (the cooperating gear not being shown herein), and the pump is provided with a suitable reversible valve system, one of each of two pairs of valves being indicated at 23 and 24 respectively, for enabling the pump to draw hydraulic fluid from a sump S in the power case and speeder case (normal fluid level at L) which communicates with a pump inlet chamber 18 in the base.

During rotation of the shaft 10 by the engine, hydraulic fluid is maintained under constant operating pressure in ducts or passages 15, 16 and 17 in cooperation with spring loaded accumulators (not shown) located at opposite sides

of the passage 16 and communicating with the duct 16 as by cross passages one of which is indicated at 19 (left Fig. 1). The accumulators maintain uniform pressure in the ducts 15, 16 and 17 in the event of overdelivery by the pump—excess fluid being discharged to the sump essentially as in the arrangement shown in said patent. Hydraulic fluid supplied to and maintained at the bore 17 under constant pressure is controlled by operation of a pilot valve (plunger 20, sleeve 21 and other elements to be described later) to effect movement of a servo-motor piston 22 in the proper direction to regulate the speed of the engine.

The pilot valve sleeve 21 is tightly fitted into a central vertical cylindrical bore 30 in a central portion of the power case which completely surrounds the valve sleeve. The valve sleeve has a cylindrical axial bore 31 which is open at both ends of the sleeve and in which various "land" portions of the pilot valve plunger are slidably fitted and enabled to rotate while maintaining respective lateral ports of the sleeve sealed, as will be apparent. The plunger has two main lands 25 and 26. The lower land 25 normally seals ports 28 of the pilot valve sleeve (open to constant pressure at the bore 17) with reference to the central bore of said sleeve. The upper land 26 normally seals ports 29 of the pilot valve sleeve (open to the sump) against communication with the central bore of the sleeve. A neck portion 35 of the pilot valve plunger maintains an open space between the valve plunger and valve sleeve which communicates at all times with a duct 36 which, in turn, communicates freely with the lower end portion of the servo-motor cylinder, i. e. below the enlarged portion 37 of the servo-motor piston 22. The ports 28 of the sleeve which are normally blocked by the land 25 communicate freely at all times with the servo-motor cylinder above the piston portion 37 through a duct 38. The reduced upward end 39 of the servo-motor piston slidably closes the upper end of the servo-motor cylinder and reduces the effective area of the servo-motor piston relative to the lower effective area of the piston, so that, with the same pressure admitted to the cylinder above and below the piston portion 37, the piston moves upwardly. The piston has a power connection (regulating rod 40) extending downwardly out of the servo-motor cylinder block through a suitable sealing ring in a head member 42 to enable regulation of the governed engine.

Downward movement of the servo-motor piston reduces and eventually cuts off power input to the engine; and upward movement admits and increases such power input.

When the pilot valve plunger 20 is moved downwardly from its normal (illustrated) position, the land 25 opens the ports 28 to the interior of the valve sleeve 21, whereupon constant pressure from the bore 17 around the sleeve is admitted to the duct 36 past the neck 35 of the valve plunger; and the servo-motor piston is raised due to the area differential of said piston.

When the pilot valve plunger is raised, the land 26—by opening the ports 29 to communication with the interior of the valve sleeve 21—dumps operating fluid from the servo-motor cylinder below the piston portion 37 to the sump through the duct 36, valve sleeve bore 31 and ports 29; and constant pressure from the bore 17 through the duct 38 to the upper side of the pis-

ton portion 37 then causes lowering of the servo-motor piston.

The pilot valve plunger is maintained in the position shown, holding the servo-motor piston against movement, during normal operation of the engine, by reason of the operation of a fly-ball mechanism 50 including a speeder spring 51 and fly-balls 52 pivoted on a rotary ball head 53. The fly-ball arms 54 bear upwardly at their inner 10 ends on a thrust member 55 rigid with the pilot valve plunger, tending to raise the plunger as the speed of the engine increases; but (e. g.), so long as the load on the engine remains constant at a given setting of the speeder spring, the downward force of the spring on the valve plunger holds said plunger against upward movement,—in other words in "balanced" position to maintain both lands 25 and 26 in closing relation to their respective ports. Friction of the 20 ball-arm fingers on the thrust member 55 causes the pilot valve plunger to rotate with the ball head during the entire operation of the governor.

The connection between the speeder spring 25 and pilot valve plunger 20 may comprise an antifriction bearing assembly as in my Patent 2,219,229, which enables free rotation of the pilot valve plunger and non-rotation of the speeder spring.

30 The ball head 53 is journaled for rotation on a reduced upper end portion 56 of the pilot valve sleeve 21. A depending hub portion 57 of the ball head which surrounds said portion 56 of the valve sleeve has gear teeth 58 which mesh with 35 a driving gear not shown on a vertical shaft, the lower end of which is drivingly rigid with the pump gear which cooperates with the pump gear 13. This ball head drive is the same as shown in said patent. The ball head 53 has a circular 40 wall portion around the fly-balls which supports a sleeve 63 extending upwardly around the fly-balls and having an inturned flange 64.

Isochronous operation of the governor requires primary and secondary compensation, as is well 45 known. The compensation system shown herein is essentially the same as that of the above identified patent and reference is directed to said patent for a more complete discussion of the same than given herein. Primary compensation 50 is effected hydraulically as a function of servo-motor piston movement; and restrains the axial movement of the pilot valve in its operation to initiate movement of the servo-motor piston, thus preventing overtravel of said piston both in retarding and increasing power input to the engine.

For primary compensation, fluid is moved in a compensation fluid duct 70 which extends through various parts essentially the same as in my said patent. A hollow piston 71 fixed to the 60 upper end of the servo-motor block 3 operates in an axial bore 72 of the servo-motor piston 22 so as to serve as an actuating compensation pump in increasing and decreasing pressure at a space 73 below the pilot valve sleeve 21 and 65 within the closed lower end of the bore 30 of the power case. The compensation fluid duct 70 is normally kept full of operating fluid from the sump through lateral holes 74 in a sleeve 74' (above servo-motor) the bore of which sleeve has restricted communication with the compensation duct 70 at the upper end of the hollow piston 71. The holes 74 are open outwardly to the sump in the speeder case.

When load on the engine drops the fly-balls 75 move outwardly, thus raising the pilot valve

plunger. As the pilot valve plunger is moved upwardly from its normally centered position—initiating a downward or power input reducing movement of the servo-motor piston—suction on the fluid in the compensation fluid duct 70 tends to evacuate the space 73 below the pilot valve sleeve. This acts, hydraulically, yieldingly to restrain the upward movement of the pilot valve plunger, by virtue of a receiving compensation piston 75 connected to the pilot valve plunger by means of a coil spring 76 capable of imparting reversible restraining action on the plunger and capable of causing the piston 75 to turn with the valve plunger in the valve sleeve. The restraint (primary compensation) is only temporary because, as soon as the servo-motor piston starts to move downwardly, fluid begins to leak into the compensation duct (secondary compensation) from the sump at holes 74 and the restricted communication thereof with the compensation duct. The rate of leakage is regulated by an adjustable needle valve pin 78 between the holes 74 and the compensation duct. The space between the receiving compensation piston 75 and the pilot valve plunger communicates freely with the sump space of the power case.

Upon increase of load, resulting in a lowering movement of the pilot valve plunger, the reverse of the above described action takes place. The resulting upward or power-input-increasing movement of the servo-motor piston moves fluid in the compensation fluid duct 70, raising or tending to raise the receiving compensation piston 75, thereby to restrain the lowering movement of the pilot valve. Secondary compensation (leakage through the restriction at the needle valve 78) removes the restraining action of the compensation piston 75 on the pilot valve plunger as the speed is brought back to normal; but the direction of fluid leakage is reversed. Fluid leaks from duct 70 into the sump.

The above described arrangement in general is the same as that of my Patent 2,219,229, and the operation thus far is also essentially the same as in said patent.

Speed adjustment

A speed control lever 80 extends diagonally of the speeder case in a horizontal plane as shown, by Fig. 2. The lever has an adjustable trunnion connection with the speeder spring in the form of a block 81 (cylindrical sleeve) pivoted on aligned pins 82 which are carried by spaced portions of the lever, and an adjustable screw 83 in the block which bears downwardly on the speeder spring and may be locked in place in the block as by a nut 84 engaging the block. The right hand end of the speed adjusting lever 80 is supported by a horizontal shaft 88 mounted in the speeder case as on pivot bolts 89 (Fig. 2), the lever 80, as shown, being suspended from the shaft by a link 85 pivotally carried on a mounting assembly 86 concentric with the axis of the shaft. The mounting assembly shown includes parts 160 and 168 which are unessential so far as the invention claimed herein is concerned—160 being a pinion adapted to be turned by teeth on a rack bar 161 supported as at 162 and extending to the upper end of the servo-motor piston 22, being held in contact with said piston by a spring 164. The vertical motion of the rack bar, as fully explained in the parent application, can be made to change the elevation of fulcrum of the speed adjusting lever (for speed droop adjustment) but said elevation will not be changed by said motion

of the rack bar in the relative adjustment of parts 86 and 160 illustrated.

Power head

5 As shown in Figs. 2 and 3 the end of the speed adjustment lever 80 opposite the fulcrum (i. e. left end, Fig. 2) is pivoted to an upright stem 90 of a power head piston 91 which operates in a vertical cylinder bore 92 formed in the speeder case, a portion of which latter (240) may extend below the top of the power case as shown in Fig. 1 to accommodate the power head. The stem 90 is slidably guided for vertical movement in a cap 93 closing the upper end of the power head cylinder bore 92. The left hand end of the lever 80 is bifurcated to straddle the stem 90 and is provided with axially aligned horizontal pins 94, the proximate ends of which pivot in a ring 95 clamped to the upper end of the power head piston stem 90.

10 The power head piston is actuated hydraulically and is controlled by a follow-up valve the stem of which is shown at 96 within an axial bore of the piston stem 90, so that the piston moves up and down with the valve, i. e. as the valve stem is moved up and down. The valve admits fluid from a constant pressure source (described later) into operative relation to the piston for movement of the latter up and down 15 exactly as the valve stem 96 is moved. The valve requires very little power to operate it, and thus the power required for changing speed, manually or by a Selsyn motor, may be made independent of the variable resistance of the speeder spring in opposing speed adjustment.

20 Constant pressure is applied to the upper side of the power head piston 91 (Fig. 3) to move the piston downwardly, through a duct comprising a vertical bore 100 (left Fig. 1) in the power case communicating with the bore 17 thereof, and bores in the speeder case comprising a diagonal bore 101, vertical bore 102 and a horizontal bore 103. The latter is shown in Fig. 3 connecting the upper end of the power head cylinder 92 with the vertical bore 102. The same pressure is applied to the lower piston face (larger) to move the piston upwardly as will be shown presently.

25 40 45 50 55 60 65 70 75 The power head valve is a cylindrical plug 105 on the lower end of the valve stem 96, which latter does not seal the bore 97 of the piston stem above the plug, whereas the plug is in sealing relation to the portion of the bore in which it slides. The plug 105 normally blocks two lateral ports 107 and 108 in the stem of the power head piston 91. The port 107 communicates freely with the power head cylinder below the piston 91 through a duct 109; and the port 108 communicates directly with the effectively smaller cylinder above the piston 91. When the plug 105 is moved downwardly by the speed setting mechanism, fluid from the cylinder 92 below the piston 91 is vented to atmosphere along the valve stem 96, i. e. between it and the piston stem 90, whereupon pressure applied above the piston (smaller effective area) moves the piston downwardly until the plug again blocks the port 107. Similarly when the plug 105 is raised it unblocks the port 108 admitting constant pressure to the lower end of the power head cylinder 92, thus raising the piston to whatever extent the plug 105 has been raised and then blocking the port 108, stopping further upward travel of the piston.

Power head operating mechanism

For operating the power head valve stem 96 there is provided, as shown in Figs. 2 and 3, a bell crank 110 pivotally supported on a horizontal shaft 111 in the speeder case. The bell crank has a horizontally extending bifurcated arm 112 provided with a pin and slot connection 113 with the upper end of the said valve stem. An upstanding arm 114 of the bell crank has a yielding lost motion connection (compressible link, including a spring 115 and bar 116) with an arm 117, which latter is keyed to a speed adjustment shaft 118 suitably mounted in the speeder case parallel to the shaft 111 and at the right thereof (Figs. 1 and 2). The bar 116 is pivotally pinned to the arm 117 at 119 and has a slot 120 slidably embracing a pin 121 on the bell crank arm 114.

A clamping means 133 holds the arm 130 on the shaft 118. The shaft 118 may carry an adjusting arm 130 having an operating wheel 140 and mechanism (not shown) connecting the wheel with a fixed quadrant bar 137 for angular adjustment of said shaft. A friction detent spring 145 on the arm slides against the quadrant bar.

For increased speed adjustment the shaft 118 is rotated counterclockwise as viewed in Fig. 1; and by virtue of the yielding lost motion connection constituted by the spring 115, slot 120 and pin 121 the shaft 118 cannot, upon turning of the shaft to increase speed—as at starting of governor operation—be moved so forcibly as to strain or break the arms 112, 114 or 117. The danger of such breakage occurring arises from the fact that, until operating fluid pressure is built up in the hydraulic system by the gear pump or otherwise, the power head piston is “oil-locked” against downward movement.

To enable the relationship between turning of the shaft 118 and adjustment of the speeder lever 80 to be changed, a slot 124 (Fig. 1) is provided in the upstanding arm 114 of the bell crank 110, and the pin 121 can be locked in various positions along the arm 114 thus changing the angle through which the bell crank (and consequently the lever 80) will swing with a given angular movement of the adjusting shaft 118. The pin 121 has a clamping nut 121a which is readily accessible through the top of the speeder case.

Booster servo

Shown at the left in Fig. 3 and located at the left in Fig. 2 is a cylinder block portion 240 of the speeder case portion which contains the power head 90 etc. previously described. Fig. 1, at the left, also shows part of the fluid duct system associated with the mechanism about to be described. The booster-servo is for enabling air pressure from the starting air line of a Diesel engine to be used to insure the building up of adequate pressure and supply of operating fluid in the governor during the operation of starting the engine, or previously.

As shown in Fig. 3 the block portion 240 of the speeder case (hereinafter for convenience block 240) is bored upwardly from the bottom at 241 to a point near the top to receive a piston 242 having an imperforate partition 243 between its ends; a downwardly projecting hollow cylinder portion 244 below the partition, and an upwardly projecting hollow cylinder portion 245 above the partition. The piston 242 is normally forced downwardly, by a strong spring 246 in the upper part of the cylinder bore 241, against a plug-

like member 247 fixed to the block 240 and which nearly closes the lower end of the cylinder bore. The member 247 has an axial bore 250 leading therethrough and having an enlarged entrance portion threaded to receive an air pipe connector fitting (not shown) of the starting air line. Pressure in such lines is usually several hundred pounds. An upper cylindrical portion of the plug-like member 247 constitutes a fixed piston mating with the lower cylinder portion 244 of the piston 242. A cup shaped flexible sealing element 252 is secured to the fixed piston 247, so that air admitted through the bore 250 thereof will raise the hollow piston 242, compressing the spring 246.

Assuming the upper part of the cylinder bore 241 contains hydraulic fluid, the air line pressure will force such fluid out of the upper end of the block 240 through a duct 253 formed by intercepting bores in the top wall of the block 240 as clearly shown. The duct 253 (cf. Figs. 1, 2 and 3) leads to the constant pressure space 17 etc. of the hydraulic system of the governor as through a vertical bore 254 (see Fig. 1) and check valve chamber 255—part of bore 102—which latter communicates with the duct comprised of bores 100 and 101 (Fig. 1) already described. The check valve chamber 255 has a spring pressed ball 257 therein operative to prevent loss of pressure from the constant pressure chambers (17 etc., including power head cylinder 92) of the governor after starting has been accomplished.

The booster-servo obtains hydraulic fluid from the speeder case portion of the sump through a duct comprising interconnected bores in the speeder case; 260, 261, 262 and 263 (Fig. 2 particularly), past a gravity seated ball check 264 (Fig. 1) in the bore 262. The bore 263 intercepts the discharge duct 253 in the top of the booster cylinder block. The ball check 264 prevents return flow of fluid to the sump from the booster cylinder when the booster-servo piston is raised in starting.

In the event the governor stands idle for some time the spring loaded pressure accumulators will ordinarily force most of the fluid out of the constant pressure spaces into the sump. In such event subsequent operation of the booster-servo piston would be resisted only by the unloaded or nearly unloaded accumulator springs. Also if fluid happened to be low in the speeder case portion of the sump at the time the booster-servo piston 242 previously descended to draw a new supply of fluid from that portion of the sump and the sump supply failed to supply fluid there would be nothing but air in the upper part of the cylinder 241 to damp the upward movement of the booster-servo piston on the next actuation. In either event damage to the upper booster-servo cylinder head portions can be prevented by the present arrangement (Fig. 3), viz.:

The upper cylinder portion 245 of the booster-servo piston slidably receives a dash pot plunger 265 having a small hole 266 extending therethrough to a downwardly open counterbore 267 of the plunger. A compression spring 268 resting on the partition 243 extends into the counterbore 267 and operates, whenever necessary, to draw fluid into the chamber below the plunger through the hole 266 until the spring has become fully extended. The hole 266 of the plunger is aligned with the vertical portion of the duct 253 so that the hole 266 cannot be sealed by engagement of the plunger with the top of the cylinder bore 241. A cross slot in the top of the plunger

265 prevents the plunger from blocking exit of hydraulic fluid from the booster-servo cylinder 241 to the duct 253 at the completion of the upward stroke of the booster-servo piston. In the fully expanded position of the spring the plunger 265 stands a short distance above the top rim of the upper cylinder portion 245 of the booster-servo piston. Thus when air is applied to raise the booster-servo piston and the piston encounters little or no resistance except that afforded by the spring 246 the impact of the booster-servo piston is cushioned by discharge of hydraulic fluid from the dash pot.

To prevent oil from entering the air starter line where it might cause an explosion if allowed to be carried into the engine along with the starting air, a vent hole is provided at 270 in the member 247 which serves as the fixed air piston. The illustrated position of the vent also prevents air which may leak past the sealing cup 252 from entering the hydraulic fluid of the governor along the outside of the hollow piston 242.

Starting air admitted to the chamber between the fixed and movable pistons 247 and 242 can be bled out of said chamber at a ball check valve 272, Fig. 3, having a ball 273 which moves outwardly against a seat 274 in a sleeve 275 (overcoming the force of the ball spring 276) when air is applied to the line and which is pushed away from the seat by the spring when the air pressure finally drops say to around 75# per sq. in.

While the booster-servo mechanism is described above as operated by the starting air line of a Diesel engine and the governor mechanism is shown as adapted for speed governing of such engine, it will be understood that the booster-servo mechanism may be operated by any kind of fluid pressure and that the governor, by appropriate adaptation as well known in the art, can be used for other purposes than speed regulation and control.

I claim:

1. In a speed governor wherein a weighing element drivingly connected to a rotary part of a mechanism to be governed controls regulation of such mechanism through a hydraulic relay, means operable by such rotary part to maintain a supply of hydraulic fluid under operating pressure during operation of the governor, said means including a reservoir for the fluid, a hydraulic booster piston and cylinder in upright position, the top of the cylinder having hydraulic fluid connections with said reservoir and said piston having a spring to force it downwardly in the cylinder capable of drawing a booster reserve supply therefrom and maintaining the reserve supply separate from the reservoir, and a motor operable by elastic fluid associated with the lower end of the booster piston and operable to cause said piston to rise in its cylinder and pump hy-

draulic fluid of the reserve supply to the reservoir for creating initial pressure upon starting of the governor operation.

2. In a governor for engines adapted to be started by compressed air, said governor employing a hydraulic fluid operated regulation system, a casing for the governor providing a normal supply for hydraulic fluid, a substantially upright booster servo cylinder bore in the casing, 10 a duct formed in the casing leading into an upper end portion of the cylinder bore and communicating with said normal fluid supply to charge the cylinder bore with hydraulic fluid from the system for subsequent redelivery to the system 15 through said duct, a booster servo-piston in the cylinder bore, a spring acting downwardly on the piston to cause the piston normally to occupy a lower end portion of the bore when the cylinder bore is charged, an air cylinder bore extending upwardly in the piston from the lower end of the piston, a fixed plug element in the lower end of the cylinder member and having a piston portion slidably fitting the air cylinder bore, a duct 20 in the piston portion of the plug element lengthwise thereof to supply air as from an engine-starting air supply to the air cylinder bore of the booster servo-piston for actuating the latter during starting of such engine, and a vent in one of said elements communicating with the lower end of the booster servo-cylinder for preventing intercharge of hydraulic fluid and air past the main cylinder surface and the air cylinder surface.
3. In a governor, weighing means responsive to a force factor of a mechanism or apparatus to be governed, a source of hydraulic pressure dependent upon sustained operation of the mechanism or apparatus to be governed, hydraulically-actuated regulating means for said mechanism or apparatus, a pilot valve operatively connected to said weighing means for controlling the supply of hydraulic fluid from said source to said regulating means, a casing, a bi-directional hydraulic motor mechanism in said casing operatively connected to and constituting an adjusting means for said weighing means and supplied with fluid from said source, and means for supplying said weighing-means-adjusting hydraulic motor mechanism with operating hydraulic fluid 40 during incipient as well as sustained operation of the mechanism or apparatus to be governed, said last-mentioned means comprising a hydraulic-pressure boosting mechanism in said casing alongside said hydraulic motor mechanism and operative, in response to a starting condition of said mechanism or apparatus, to boost the hydraulic pressure derived from said source and delivered to said motor mechanism to a value sufficient to operate said motor mechanism at the inception of operation of said mechanism or apparatus 45 to be governed.
